FABRIC.

No. 18,349.

Patented May 22, 1888.

UNITED STATES PATENT OFFICE.

CHARLES B. SMITH, OF FITCHBURG, MASSACHUSETTS.

DESIGN FOR FABRIC.

SPECIFICATION forming part of Design No. 18,349, dated May 22, 1888.

Application filed April 13, 1888. Serial No. 270,599. Term of patent 3½ years.

To all whom it may concern:

Be it known that I, CHARLES B. SMITH, of Fitchburg, in the county of Worcester and State of Massachusetts, have invented and produced a new and original Design for Fabric, of which the following is a full, clear, and exact specification.

My new design is fully illustrated in the accompanying photograph, to which reference is made.

A B represent alternating stripes. The stripes A show narrow parallel lines or ribs a running diagonally across said stripes from

edge to edge. The stripes B each show diagonal ribs b b, alternated by diagonal stripes c c. 15 I claim—

The design for fabric herein shown and described, the same consisting of the stripes A B, alternating each other, the stripes A showing diagonal lines a, the stripes B showing 20 diagonal ribs b and diagonal stripes c, alternating the diagonal ribs b.

CHARLES B. SMITH.
